LAVATORY

Norman Van Skyhawk, Salt Lake City, Utah, assignor to
American Standard Inc., New York, N.Y.

Filed Oct. 6, 1969, Ser. No. 19,437

Term of patent 14 years

Int. Cl. D23—02

U.S. Cl. D23—58

Fig. 1.

Fig. 2.

Fig. 3.

Fig. 4.

FIG. 1 is a top plan view of a lavatory embodying my new design.

FIG. 2 is a front elevational view thereof.

FIG. 3 is a side elevational view thereof.

FIG. 4 is a cross-sectional view taken on line 4—4 of FIG. 2.

I claim:

The ornamental design for a lavatory, as shown.
